UNITED STATES PATENT OFFICE.

AUGUST H. HOENISCH, OF PHILADELPHIA, PENNSYLVANIA.

SHADE-ROLLER BRACKET.

1,120,494.

Specification of Letters Patent.

Patented Dec. 8, 1914.

Application filed March 14, 1914. Serial No. 824,628.

To all whom it may concern:

Be it known that I, AUGUST H. HOENISCH, a citizen of the United States, residing at Philadelphia, in the county of Philadelphia and State of Pennsylvania, have invented a Shade-Roller Bracket, of which the following is a full and complete specification.

My invention is an improvement in brackets for window curtain fixtures, and relates more especially to that particular class of brackets which are employed for supporting the ordinary spring-roller for curtain-shades.

15 The conventional form of shade-roller bracket is provided with a base or attaching-flange having holes through which the attaching nails or screws are driven into the window-casing, and inasmuch as the body 20 of the bracket projects outward from the base or flange considerable difficulty is experienced in driving the attaching means, especially when nails are employed; such difficulty being enhanced by the location, for 25 the insufficient light on the bracket and the glare from the window interfere materially with the operation of driving. It is preferable therefore to provide the bracket with integral attaching means, as a screw, and 30 to have said screw either an integral part of the bracket or firmly and securely attached thereto in such manner as to withstand the operation of driving as well as form a proper supporting-bracket for the roller 35 and curtain-shade.

The primary object of my invention, therefore, is to provide a shade-roller bracket which can be readily and conveniently secured in its proper place on the 40 window casing and without the employment of extraneous attaching means.

A further object of my present invention is to provide a shade-roller bracket which can be cheaply manufactured from sheet-45 metal and supplied with an ordinary wood-screw rigidly connected thereto, thus producing a single article of this character in a single piece and at a minimum price.

Other objects and advantages will herein-50 after appear, and what I claim as new in the particular construction of the bracket is more specifically set forth in the appended claim.

In the accompanying drawings, which 55 form a part of this specification: Figure 1 is a side view of a shade-roller bracket con-

structed in accordance with my present invention. Fig. 2 is a view illustrating the application of the bracket in supporting one end of a curtain-shade roller. Fig. 3 is a similar view showing its application in supporting the other end of the roller. Fig. 4 is a transverse sectional view, on the line 4-4 of Fig. 1. Fig. 5 is a longitudinal sectional view on the line 5-5 of Fig. 1. Fig. 6 is a detail view of the bracket-plate, showing the means employed for attaching the screw thereto. Fig. 7 is a detail view of the attaching-screw which is connected to the bracket-plate. Fig. 8 is a detail view of the washer or disk employed in connecting the bracket-plate and screw.

Like numerals of reference indicate like parts in all the figures of the drawings.

In carrying out my invention the bracket 75 is preferably formed from sheet-metal or a plate of suitable thickness stamped or otherwise shaped to provide a circular member or shank 10, and a companion supporting-member 11, the latter having an open-end receiving slot 12, hereinafter particularly described, and in the present instance this bracket-plate is provided with an attaching-screw 13, firmly and securely connected thereto so as to constitute a rigid 80 part thereof.

For the purpose of rigidly connecting the bracket-plate and screw together the head and shoulder portion of the latter is provided with a transverse slot 13^a of a suitable 90 depth to receive a tongue 14, formed at the inner end of the circular member or shank 10 of the bracket-plate, and in connection with the tongue I may and preferably do employ a washer or disk 15, which in the 95 present instance serves to more intimately bind the several parts of the bracket together in one piece. This metal disk is provided centrally with a circular opening 15^a, through which the body portion of the 100 screw is passed so that the head thereof may bear against said disk, and also with slots 15^b, 15^b, at opposite sides of the opening and communicating therewith, to receive the tongue 14 when the parts are assembled.

It will be noted that the bracket-plate is provided at the inner end of the tongue 14 with opposite shoulders 16, 16, which bear against the disk beyond the ends of the tongue-receiving slots 15^b, and in the present 110 instance the metal disk is slightly dished, and the aforesaid shoulders correspondingly

curved to provide a close joint between the bracket-plate and disk. It will also be noted that when the tongue 14 of the bracket-plate is passed through the head of the screw, 5 openings in the disk and into the shoulder of said screw the outer corner portions of the aforesaid tongue will be disposed at opposite sides of the shoulder of the screw and beyond the outer face of the metal disk, 10 as indicated in dotted lines in Fig. 6 of the drawings, whereby the several parts may be intimately and rigidly connected together by upsetting or riveting said corners against the screw and disk. However, in some instances 15 the parts when assembled as hereinbefore described may be secured together by electric welding; and in either case the screw becomes practically an integral part of the bracket-plate so as to provide a one-piece 20 shade-roller bracket combining bracket and attaching means, the metal disk not only serving to bind the other parts but also forms a binding-shoulder adapted to bear against the window-casing when the screw 25 is driven home.

The slot 12 in the bracket-plate is of a peculiar shape to receive either the oblong gudgeon 17 at one end of the shade-roller or the round gudgeon 18 at the other end, 30 whereby the same form of bracket may be used to support both ends of the roller instead of employing one with a hole and another with a slot, as heretofore. For this purpose said slot is shaped to provide an 35 entrance opening 12^a, disposed at an angle of 45 degrees to the axis of the attaching-screw, and extending rearwardly from the forward upper end of the supporting member 11, said opening communicating with a 40 downwardly extending passage 12^b, disposed at right angles thereto and connecting at its lower end with a rectangular recess 12^c in the front wall of said passage, and in the present instance the lower end of the passage 45 12^b is formed with a curved bottom 12^d, forming a seat for the round gudgeon or pin 18 when the bracket is used to support this end of the shade-roller. The width of the entrance opening and communicating 50 passage is such that the round gudgeon may be passed through the same to engage the seat 12^d; and in like manner the oblong gudgeon 17 may be passed through the entrance opening and passage to engage in the 55 recess 12^c of a companion bracket; or either gudgeon may be first placed directly in engagement with its seat by moving the shade-roller laterally into such engagement and

the other gudgeon then slid into the companion bracket in the manner hereinbefore 60 described. However, it may be more convenient to place both gudgeons of the shade-roller in engagement with their respective brackets simultaneously, and to facilitate the operation of entering either gudgeon 65 into the entrance-opening of its bracket the upper wall of said entrance opening is preferably extended slightly beyond the plane of the front edge of the bracket, whereby the gudgeon may be placed against said edge 70 and when slid upward thereon will strike the projecting upper wall and be guided thereby into the receiving-slot.

From the foregoing description in connection with the accompanying drawings it 75 will be seen that I provide a shade-roller bracket that can be manufactured very cheaply, inasmuch as the bracket-plate, with its gudgeon-receiving slot 12 and connecting-tongue 14, may be easily stamped from sheet metal and the disk and screw connected thereto at very little additional cost. The completed bracket is in one piece and in applying the same to the window-casing 85 the bracket-plate forms a convenient grip for driving or turning the attaching-screw, and of course as the bracket is designed to receive either a round or oblong gudgeon two similar brackets are used to support a shade-roller, a feature possessing obvious 90 advantages over the old style of shade-roller brackets in which one is provided with a hole and the other a slot.

Having thus described my invention, I 95 claim:

A shade-roller bracket, comprising a plate having a gudgeon-receiving slot at its forward end and a tongue at its rear end, an attaching-screw having a slot in its head and shoulder in which the aforesaid tongue fits, and a disk having an opening receiving the screw and tongue, said parts being secured together; the gudgeon-receiving slot at the forward end of the plate having an entrance opening leading downwardly and rearwardly, a communicating passage extending from the inner end of the entrance opening at an angle thereto and curved at its lower end to form a seat, and a rectangular recess at one side of the lower end of the aforesaid passage, substantially as shown and described.

AUGUST H. HOENISCH.
